(57) **CLAIM**

The ornamental design for a refrigerator lock, as shown and described.

DESCRIPTION

- 1.1 is a front view of the refrigerator lock;
- 1.2 is a back view thereof;
- 1.3 is a left view thereof;
- 1.4 is a right view thereof;
- 1.5 is a top view thereof;
- 1.6 is a bottom view thereof;
- 1.7 is a first perspective view thereof;
- 1.8 is a second perspective view thereof;
- 1.9 is a third perspective view thereof;
- 1.10 is a fourth perspective view thereof.
